Fig. 4

FIG. 1 is a top plan view of a candle holder showing my new design.

FIG. 2 is a side elevation thereof.

FIG. 3 is a transverse cross-sectional view of one of the arms of the candle holder illustrated in FIG. 2.

FIG. 4 is a central transverse cross-sectional view of the base of the candle holder shown in FIG. 2.

The essential features of my design reside in the complementary reverse adjoining curved configurations on the top of the base and the arm supporting the sockets, the opposite edges of the upper surfaces of said curved configurations being similarly bevelled.

I claim:

The ornamental design for a candle holder, substantially as shown and described.
